HAT ADJUSTING MEANS

Ruby Lipton Brill and Sarah Lipton, Long Beach,
N. Y.

Application July 22, 1942, Serial No. 451,848

4 Claims. (Cl. 132—59)

This invention relates to hats and to means for adjusting a hat to the head of the wearer.

In millinery shops a great variety of styles of hats must be carried, and since there are many different head sizes, the amount of stock which must be kept on hand is very large. The ordinary hat has no provision for adjustment to the head of the wearer so that between two standard sizes the customer is forced to elect the size which is nearest to a fit without securing an exact fit.

It has previously been proposed to provide various means for reducing the head size of a hat but these means have in general possessed the disadvantages that they must be sewn into the hat or stitched through the hat band, both of which operations are time consuming and, because of the nature of the retail trade in hats, often result in loss of sales which otherwise could be quickly consummated. Other prior constructions have been of a too bulky nature to justify their use on the hat band.

It is an object of the present invention to enable a hat to be quickly and conveniently modified, without alteration of the external appearance, so that it will snugly fit a head somewhat smaller than that for which it was designed, by securing adjusting means to two spaced points in the upper or free margin of the hat band and by providing a third point of securing intermediate said spaced points, also in the hat band.

It is an object of the invention to provide a hat size adjuster which will cause contraction of the hat band to be distributed substantially equally between the two outer points of connection thereto.

For the accomplishment of these objects provision is made in accordance with the present invention of a device having a flexible connecting element, anchor pins at each end thereof adapted to hold and engage cords or the like, said pins being insertable through the hat band at spaced points thereon and when inserted being self locking therein. The flexible connecting element may be of cord or webbing or both and may be of elastic or non-elastic material as desired. A further feature of the invention is the provision substantially equidistant between said pins of a third anchor member of similar character to those at the ends of the adjusting device which third anchor member is carried by said flexible connecting element and centers the adjusting device and holds it snugly about the inner margin of the crown of the hat adjacent the brim thereof thus avoiding bridging of the device

across the head opening. The cords and webs of material may be of any desired length to suit the needs of the hat to which the device is applied. Other objects and advantages will hereinafter appear from the description and the drawing forming a part of this specification and illustrating certain preferred embodiments of the invention wherein:

Figure 1 is a front view of a hat looking underneath the brim and into the crown;

Figure 2 is a view showing the adjusting device as used in Figure 1;

Figures 3, 4, 5 and 6 are views similar to Figure 2 showing modifications of the adjusting device shown in Figure 2, and

Figure 7 is a fragmentary view of an alternate disposal of parts of the device shown in Figure 5. The hat 10 comprises a brim 12 and a crown 14. A band 16 is secured to the inner lower margin of the crown by any convenient means such as sewing, leaving the upper portion of the band 16 free to move away from the crown. As shown in Figure 1, the device of Figure 2 is mounted on the band and being thus mounted contracts the circumference of the band 16 and thus reduces the head size of the hat 10 whereby the hat fits snugly on the head of the wearer.

Referring to Figure 2, the device shown comprises anchor pins 18 which have points 20 insertable through the hat band material. The pins 18 have tubular bodies 24 which are clamped upon loops 22 of cord. Joining the loops 22 are the webs or ribbons 26 and 28 which webs have stitched loops at either end thereof through which the loops 22 extend as shown. Webs 26 and 28 may, as shown, cross at the central portions thereof and at the point of crossing, a loop of cord 30 may be inserted which has its ends clamped in pin 32 which may be similar to the pins 18. If desired, of course, any of the loops may be formed by inserting one of the cord ends in the pin or needle and tying the other about it near its point of attachment as shown in Figure 7. Loops 22 and the webs 26 and 28 comprise a flexible connecting element between pins 18 and with the loop 30 may be formed of any convenient material according to the desires of the manufacturer, it being preferable, however, that some portion of the device upon which tension is exerted shall be of elastic material of cloth, rubber or the like. Thus either the loops or webs or both may be elastic.

It will be seen that when it is desired to reduce the size of a hat to fit a head size smaller than the actual size of the hat, it is only necessary

for the pins 18 to be inserted, preferably at points equi-distant from the rear of the hat, in the hat band as shown in Figure 1. The pin 32 may then be inserted in the band at a point substantially equi-distant from the points of connection of the pins 18. This latter mentioned pin has the double advantage of providing secure connection for the device to the band of the hat and of insuring that the device will not bridge between the two extreme points of connection, thus rendering it difficult for the wearer to don the hat. When the pins are applied, they are completely concealed behind the hat band so that a neat appearance is presented and there is no danger of the pins becoming entangled in the hair. It is further noted that the operation of applying the device is entirely free of the disadvantages arising from sewing or stitching elastic webbing or the like into the band and yet the device of this invention is just as securely fastened to the hat as it would be by the tedious prior art methods.

Figure 3 illustrates a slight modification of the construction shown in Figure 2. In addition to the webs 33 and 35 which correspond to the webs 26 and 28 of Figure 2 and in this construction may preferably be of elastic material, a longer and broader web 34 is provided, formed with stitched loops 36 and 38 at each end thereof through which the loops 37, which correspond to loops 22 of Figure 2, pass. The web 34 may preferably be of some non-elastic material such as an ornamental ribbon and may further preferably be of considerably greater length than the non-extended length of the elastic webs 33 and 35 so that when the device is in non-extended condition, as illustrated in Figure 3, the web 34 will be somewhat creped. The center engaging member comprising the cord 30a held in loop form by pin 32a is similar to that shown in Figure 2 and serves the same purpose. The construction of Figure 3 possesses the advantages of that of Figure 2 and in addition, the advantage that the webs 33 and 35 may be placed against the hat band and the web 34 which is flat and relatively smooth when extended will be the only surface exposed to the hair of the wearer so that donning the hat will not disturb the condition of the hair of the wearer.

In Figure 4 is illustrated a construction which is particularly desirable where more strain will be placed upon the anchor pins, as more pins are provided in this construction to distribute the strain more easily. In this construction a pin may be inserted through the hat band adjacent the upper and lower margins thereof, thus distributing the strain and contracting the band evenly which will prevent discomfort to the wearer from uneven folds in the hat band. This type of adjuster is particularly useful where it is desired to make relatively substantial adjustments in hat sizes. The construction includes the double loops 40a and 40b on either end thereof each of which is held in loop form by its pins 42a and 42b. The loops may as before be of any convenient material, elastic or not. Engaging each of the loops 40a and 40b are the stitched loops 46 and 48 of web 44 which is doubled back upon itself to make this connection. Central loop 50, which is held in place by anchor pin 52, provides the connection between the two webs 44, the webs 44 being folded therearound. This construction may be simply applied to the hat by inserting the pins 42a and 42b in any convenient position on the hat band, or its equivalent,

inside the crown, and centering its position by insertion of the pin 52 in a convenient place. It will be seen that the strain caused by the application of the hat to the head is distributed between the pairs of pins 42a and 42b and thus evenly over the width of the hat band whereby a construction of considerable sturdiness is provided.

Referring now to Figure 5, a construction is shown in which the flexible connecting element includes the crossed cords 54 and 56, each of which has mounted on either end thereof an anchor pin 58. Buckle 60 or a similar engaging device, which may be a clip, an adhesive connection or a knot, is preferably associated with the cords 54 and 56 in a manner to bring the two cords into close proximity with each other and is furthermore preferably slidably mounted on the cords 54 and 56 so that it may be conveniently positioned anywhere along the length of said cords and will have the effect of bringing the cords together at whatever point it is placed. Loop 62 is threaded through buckle 60 and carries pin 64 and provides central positioning as in the other constructions described. The construction of Figure 5 is particularly advantageous in that it is extremely inexpensive requiring only the two cords and the small central loop together with the pins and buckle or its equivalent. It is applied in the same manner as described for the other constructions except that if the central point of the cords 54 and 56 is inconvenient for the insertion of the pin 64 when the pins 58 have been placed in the hat band, the buckle 60 may be slid in either direction to provide a convenient attachment point for the pin 64. In Figure 7 is illustrated the position assumed by the cords 54 and 56 when passed through the buckle but uncrossed.

In Figure 6 is illustrated a further modification of our invention in which the connecting element includes the looped cords 68 and 70 which may be of similar material to those already described and may be resilient or not as desired. The cords 68 and 70 have their ends clamped respectively in pins 72 and 74 which pins are preferably of the anchor type as described heretofore. The cords 68 and 70 are preferably looped through each other as at 76 and the short central loop 78, carrying pin 80, engages both cords 68 and 70 as shown. This construction is extremely simple in that it includes only the cords and pins, and may be conveniently applied to a hat in the same manner as set forth heretofore in connection with the other forms.

It is understood, of course, that any suitable width or length of materials may be used for the construction of the various adjusters and that any cords, ribbons or the like, either of resilient or non-resilient construction, may be employed. Furthermore, any suitable type of attaching pin means may be employed.

While we have illustrated and described in detail certain preferred forms of our invention, it is to be understood that changes may be made therein and the invention embodied in other structures. We do not, therefore, desire to limit ourselves to the specific constructions illustrated, but intend to cover our invention broadly in whatever form its principle may be utilized.

We claim:

1. A device for adjusting a hat to the wearer's head comprising a pair of flexible cords formed into loops, the ends of said loops having anchor

pins secured thereto adapted to engage the hat at spaced points adjacent the inner base of the brim, said loops being formed around each other and a third cord forming a loop around both of said first mentioned loops, said third cord having an anchor pin secured to its end adapted to engage the hat at a point between said spaced points.

2. A device for adjusting a hat to the wearer's head comprising a pair of interlinked flexible cord loops, at least one of which is formed of elastic cord, the ends of the cords forming each loop being brought together and clamped into loop form by means of a hollow anchoring pin clamped thereon, said pins being adapted to be inserted through the hat band material so as to lock behind the same, and a third cord loop interlinked through the interlinked ends of said first two loops, the ends of said third cord loop being brought together and clamped in a hollow anchoring pin also adapted to be inserted through the hat band material so as to lock behind the same.

3. A device for adjusting a hat to the wearer's head comprising a pair of interlinked flexible cord loops, at least one of which is formed of elastic cord, the ends of the cords forming each loop being brought together and clamped into loop form by means of a hollow anchoring pin clamped thereon, said pins being adapted to be inserted through the hat band material so as to lock behind the same.

4. A head size adjusting device for hats having a flexible connecting element, anchor pins on either end thereof and an anchor pin carried by said flexible connecting element intermediate said end pins, each of said pins being adapted to be inserted through and locked behind a hat band, said intermediate pin being mounted on a cord loop threaded through said flexible connecting element.
